UNITED STATES PATENT OFFICE.

JAN ARTHUR KUYSER, OF SALE, ENGLAND, ASSIGNOR TO WESTINGHOUSE ELECTRIC
AND MANUFACTURING COMPANY, A CORPORATION OF PENNSYLVANIA.

DYNAMO-ELECTRIC MACHINE.

Specification of Letters Patent. Patented Jan. 27, 1920.

1,329,247.

Application filed October 27, 1915. Serial No. 58,259.

To all whom it may concern:

Be it known that I, JAN ARTHUR KUYSER, a subject of the Queen of Holland, and a resident of Sale, in the county of Chester, 5 England, have invented a new and useful Improvement in Dynamo-Electric Machines, of which the following is a specification.

My invention relates to dynamo-electric machines, and it has for its object to provide an improved means for ventilating the 10 magnetizable core members of such machines.

A usual means for the ventilation of a core member comprises a plurality of radial vent 15 tilating passages formed by spacing apart certain of the laminae of which such member is composed. Longitudinal ventilating passages are also formed by providing suitable openings in the laminae that are ar 20 ranged to register and thus form continuous channels or passages which extend parallel with the axis of the machine. Various systems have been proposed in which the ventilating medium is caused to pass through the 25 radial and longitudinal passages, either independently or first through one and then through others of said passages. For example, in one arrangement, the ventilating or cooling air passes first into certain radial 30 passages, then along certain longitudinal passages and finally passes out through other radial passages. In other arrangements, the cooling air enters through the longitudinal passages and then passes out 35 through the radial passages to which all of said longitudinal passages are connected.

According to my invention, the cooling air is made to take a path which is different from that employed in any of the systems 40 heretofore suggested, by causing it to pass first through a longitudinal passage and then through a selected radial passage, the air being finally discharged into the atmosphere through the shell or frame of the machine. By this arrangement, the cooling 45 effect is so regulated that an ample supply of air will be provided for all portions of the core member and an even temperature maintained throughout its entire mass.

50 An important advantage which is thus obtained lies in the fact that each air current will follow a definite path with a freedom from interference by air currents flowing in other parts of the core member.

In the accompanying drawings, Figure 1

is a front view of a portion of a lamina used in the construction of a core member in accordance with my invention; Fig. 2 is a longitudinal sectional view of a dynamo-electric machine constructed in accordance 60 with my invention, the section through the laminae comprising the core member being taken along the line II-II of Fig. 1; Fig. 3 is a sectional view similar to Fig. 2, the section through the laminae being taken along 65 the line III-III of Fig. 1. Fig. 4 is a front view, similar to Fig. 1, showing a modification in the form of the lamina; Figs. 5 and 6 are sectional views similar to 70 Figs. 2 and 3, respectively, the sections through the laminae being taken along the lines V-V and V-VI of Fig. 4.

Referring to Fig. 2 of the drawings, the stationary member of a dynamo-electric 75 machine comprises a shell or frame 1 and a plurality of assembled laminae 2 that are secured thereto in any suitable manner. The rotatable member of the machine comprises a plurality of laminae 3 that are mounted on a shaft 4 in any suitable manner. The 80 laminae 2 and 3 are assembled in groups between suitable spacing pieces so as to form a number of radial passages 5 to 13, inclusive. As best shown in Fig. 1, the laminae 2 comprising the stator core are severally 85 provided with openings 14 to 18, inclusive, that are adapted to register when the laminae are assembled so as to form longitudinal 90 passages in the core. Corresponding openings are provided in the end plates 19, 20. The end portions of the stator winding 21 are inclosed by end bells 22, and the rotor 95 is provided, at each end, with fan blades 23 by means of which air may be forced from the end bell 22 into the longitudinal passages 14 to 18, inclusive, of the stator core and also into the annular space or air gap 24 between the stator and the rotor. Air 100 also passes into an annular passage 25 provided in the rotor and from thence through the radial passages 5 to 13, inclusive, and out into the air gap 24.

The radial passages 5 to 13, inclusive, in the stator core are not all connected to all of the longitudinal passages 14 to 18, inclusive, as the latter are made continuous by means of tubes 26 that bridge the radial 105 passages and connect the oppositely-disposed openings in the laminae forming the side walls of the radial passages. The tubes 110

26 may project into the openings in the laminæ or may be united to one of the laminæ forming one side of the radial passage, for example, by the process commonly known as spot welding. In the arrangement shown in the drawings, the tubes 26 have a length equal to the width of the radial passages and form spacing pieces which may take the place of, or, be additional to suitable spacing ribs. Where it is desired that a longitudinal passage shall communicate with a radial passage, a semi-cylindrical member may be employed, as shown at 27 to 31, inclusive, in Figs. 2 and 3 for example, or the tube may simply be omitted at this point. The continuity of the longitudinal passages is interrupted between the radial passages with which the longitudinal passages communicate and the next adjacent radial passages so as to force the air to pass radially outward at this point. This interruption may be conveniently effected by filling the openings in the adjacent lamina by means of suitable disks 32, or special laminæ may be provided for those placed in which selected openings are omitted. A longitudinal passage may be connected to more than one radial passage if desired, preferably however, it is connected with one only. The number of longitudinal passages which are connected to each radial passage is determined by the quantity of cooling air that must be supplied to that part of the core in which a particular passage is located, the object being, as hereinbefore stated, to equalize the temperature throughout the entire core, as far as possible.

The selection of certain radial passages for connection to different longitudinal passages permits of the application of the counter-flow principle to the air currents traversing the core member. As shown in Figs. 1, 2 and 3, for example, the air coming from the right-hand end of the machine is arranged to pass through the longitudinal passages 18 as far as the radial passage 5, that passing through the longitudinal passages 16 passes out by the radial passage 7 and that passing through the longitudinal passages 14 passes out through the radial passage 9. The air passing through the longitudinal passages 17 is arranged to pass out by the radial passage 13 and that through the longitudinal passages 15 passes out through the radial passage 11. On the other hand, the air which is supplied from the left-hand end of the machine passes through the longitudinal passages 17 and out by the radial passage 12, through the passages 15 and out by the passage 10, through the passages 14 and out by the passage 8 and through the passages 16 and out by the passage 6. The direction of the air currents is indicated by arrows, and it will be seen that, in general, throughout the stator core cool-

ing air will be flowing through one longitudinal passage in one direction and in an adjacent passage in the opposite direction. Obviously, this counter-flow principle can not be conveniently applied to the whole of the stator core. This will be appreciated from a comparison of Figs. 2 and 3 of the drawings; for example, near the right-hand end of the core it will be seen that, in the first two sections of the core, namely, as far as radial passage 12, the air is flowing in the same direction through all the longitudinal passages and this is also true of the first section at the left-hand end of the core; that is to say, from the end plate as far as the radial passage 5. Generally speaking, it will not be necessary to carry the counter-flow principle further because differences of temperature which may arise will be compensated by the heat conductivity of the metal.

Another method of applying the counter-flow principle is by dividing the longitudinal passages into two sets, the passages of one set alternating with those of the other set, and cooling air being supplied to one set from the other end of the machine. The sets of longitudinal passages respectively communicate with radial passages at the opposite ends of the machine. For example, the longitudinal passages 14, 16, 18 may be supplied with air from the right-hand end of the machine and communicate with radial passages near the left-hand end, while the longitudinal passages 15 and 17 may be supplied with air from the left-hand end of the machine and communicate with radial passages near the right-hand end. Various other methods of arranging the connections between the longitudinal and radial passages may be employed in order to suit particular conditions.

The machine shown in Figs. 4 to 6 differs from that shown in Figs. 1 to 3 only in the arrangement of the openings in the laminæ 2, as will be seen from a comparison of Figs. 1 and 4. The arrangement of the connecting tubes 26 and the sequence of the connections between the longitudinal passages and the radial passages whereby the air currents are constrained to flow in opposite directions in adjacent longitudinal passages is substantially the same as that described with reference to Figs. 2 and 3 and need not be further described.

From the foregoing description, it will be obvious that each unit volume of the core will be supplied with equal volumes of cooling air, since equal volumes of air are supplied to each longitudinal passage, one of which discharges on either side thereof. For each of said longitudinal passages delivering air to one side of a core unit which is longer than the average length of said passages there is an oppositely disposed cor-

respondingly shorter passage delivering air to the opposite side of said unit. Thus it will be seen that, although one of the said longitudinal passages is longer than the average and the air carried thereby will therefore be at a higher temperature than the average, the correspondingly shorter passage will deliver an equal volume of air, at a temperature correspondingly lower than the average, to the same portion of the core, so that the volume and also the average temperature of the air delivered to each unit volume of the core is the same, thus causing each unit volume of said core to be supplied 15 with quantities of air of equal calorific cooling power.

While I have shown my invention in its more simple and preferred forms, it is not so limited but is susceptible of various other 20 modifications within the scope of the appended claims.

I claim as my invention:—

1. A magnetizable core member for dynamo-electric machines provided with a plurality of intersecting longitudinal and radial ventilating passages, certain of said longitudinal passages being continuous through certain of said radial passages and communicating with others of said radial 30 passages.

2. In a dynamo-electric machine, the combination with a magnetizable core member provided with a plurality of intersecting longitudinal and radial ventilating passages and means for producing air currents, of means embodied in the said core member for causing the air currents flowing through certain of said longitudinal passages to flow across certain of said radial passages and 40 to flow into others of said radial passages.

3. In a dynamo-electric machine, the combination with a magnetizable core member provided with a plurality of intersecting longitudinal and radial ventilating passages 45 extending therethrough and means for producing air currents, of means embodied in the said core member for causing independent air currents to flow in opposite directions in adjacent portions of different longitudinal passages.

4. In a dynamo-electric machine, the combination with a magnetizable core member provided with a plurality of intersecting longitudinal and radial ventilating passages 55 extending therethrough and means for producing air currents, of means embodied in the said core member for causing the air

currents flowing in the same direction in adjacent longitudinal passages to enter different radial passages.

5. In a dynamo-electric machine, the combination with a magnetizable core member provided with a plurality of intersecting longitudinal and radial ventilating passages and means for producing air currents therethrough, said longitudinal passages being continuous through certain of said radial passages, for causing substantially equal volumes of air to be supplied to all of said longitudinal and radial passages.

6. A magnetizable core member for a dynamo-electric machine provided with a plurality of continuous longitudinal passages intersecting a plurality of radial passages and means whereby said longitudinal passages are caused to communicate with certain of said radial passages and to intersect the remainder of said radial passages without communicating therewith.

7. In a dynamo-electric machine, the combination with a magnetizable core member provided with a plurality of intersecting longitudinal and radial ventilating passages, and means for producing air currents therethrough, said longitudinal passages communicating with certain of said radial passages and intersecting the remainder of said radial passages without communicating therewith, said longitudinal and radial passages being so disposed and of such cross-section as to deliver equal volumes of air to each unit volume of said core.

8. In a dynamo-electric machine, the combination with a magnetizable core member provided with a plurality of intersecting longitudinal and radial ventilating passages, of means for producing air currents therethrough, said longitudinal passages communicating with certain of said radial passages and intersecting the remainder of said radial 95 passages without communicating therewith and said longitudinal and radial passages being so disposed and of such cross-section as to deliver volumes of air of equal calorific cooling power to each unit volume of said core.

In testimony whereof, I have hereunto subscribed my name this fifth day of October 1915.

JAN ARTHUR KUYSER.
